(57) **CLAIM**

The ornamental design for pneumatic fastener application tool, as shown and described.

DESCRIPTION

FIG. 1 is a side elevational view of a pneumatic fastener application tool according to one embodiment of the present invention;

FIG. 2 is a rear elevational view thereof;

FIG. 3 is a top plan view thereof;

FIG. 4 is a bottom plan view thereof;

FIG. 5 is a perspective view thereof; and,

FIG. 6 is a perspective view of a pneumatic fastener application tool according to a second embodiment of the present invention. The other views of this embodiment correspond to the views of the first embodiment and are the same except for the differences in the height and width of the lower bar element.

Where included, broken lines showing environment or structure are for illustrative purposes only and form no part of the claimed design.
